DESIGN FOR A KEY CHARM

Melvin Jones, Chicago, Ill., assignor to International Association of Lions Clubs, Chicago, Ill., a corporation of Illinois

Application May 26, 1941, Serial No. 101,133

Term of patent 14 years

To all whom it may concern:

Be it known that I, Melvin Jones, a citizen of the United States, residing at Chicago, in the county of Cook and State of Illinois, have invented a new, original, and ornamental Design for a Key Charm, of which the following is a specification, reference being had to the accompanying drawing, forming a part thereof.

Fig. 1 is a front elevational view of a key charm showing my new design; and

Fig. 2 is a side elevation of the same.

I claim:

The ornamental design for a key charm, as shown.

MELVIN JONES.
